(57) CLAIM

The ornamental design for a woman's poncho with front pockets and hood, as shown and described herein.

DESCRIPTION

FIG. 1 is a front elevation view of the woman's poncho with front pockets and hood, showing my new design;

FIG. 2 is a rear elevation view thereof;

FIG. 3 is a left side elevation view thereof;

FIG. 4 is a right side elevation view thereof;

FIG. 5 is a top plan view thereof; and

FIG. 6 is a bottom plan view thereof.

FIG. 7 is a front elevation view of the woman's poncho with front pockets and hood, showing my new design, with the hood rolled down;

FIG. 8 is a rear elevation view thereof;

FIG. 9 is a left side elevation view thereof;

FIG. 10 is a right side elevation view thereof;

FIG. 11 is a bottom plan view thereof; and,

FIG. 12 is a top plan view thereof.

The broken lines are for environmental purposes only and form no part of the claimed design.

1 Claim, 8 Drawing Sheets
